COMBINED WOOD AND COAL BURNING STOVE

Filed Oct. 13, 1922

FIG. 2.

FIG. 1.

FIG. 3.

FIG. 4

By *J. Howard*
Attorney

UNITED STATES PATENT OFFICE.

JAMES HOWARD, OF SOUTH PORCUPINE, ONTARIO, CANADA.

COMBINED WOOD AND COAL BURNING STOVE.

Application filed October 13, 1922. Serial No. 594,273.

To all whom it may concern:

Be it known that I, JAMES HOWARD, a citizen of Canada, residing at South Porcupine, in the Province of Ontario, Dominion of Canada, have invented certain new and useful Improvements in Combined Wood and Coal Burning Stoves, of which the following is a specification.

This invention relates to certain new and useful improvements in combined wood and coal burning stoves wherein separate combustion chambers are provided for the burning of wood and coal, the combustion chamber or fire pot for the burning of wood being disposed at the upper end of the stove above the coal burning fire pot so that the heat rising from the burning coal will permit the drying of damp or green wood to be burned.

A further object of the invention resides in the provision of a combined wood and coal burning stove wherein a damper positioned adjacent the upper end of the stove casing and in the main flue of the stove is operable for controlling the flue passage from either the wood or the coal burning chambers.

The invention further provides in a combined wood and coal burning stove, a single ash pit with an inclined ledge or partition wall interposed between the upper wood burning chamber and the lower coal burning chamber, a gravity chamber being associated with the inclined partition forming a closure for the rear end thereof and shutting off communication with the main flue, while an automatically operating gravity damper is associated with the lower end of the flue for directing the wood ashes into the ash pit.

With the above and other objects in view, the invention consists of the novel form, combination and arrangement of parts hereinafter more fully described, shown in the accompanying drawing and claimed.

In the drawing, wherein like reference characters designate corresponding parts throughout the several views,

Figure 1 is a front elevational view of a combined wood and coal burning stove constructed in accordance with the present invention,

Figure 2 is a vertical sectional view of a combined wood and coal burning stove constructed in accordance with the present invention, showing the separate wood and coal

burning chambers and the several dampers associated therewith,

Figure 3 is a top plan view of the stove, and

Figure 4 is a horizontal sectional view taken on line IV—IV of Fig. 2 showing the wood burning grate and the damper plate associated with the upper end of the stove flue.

Referring more in detail to the accompanying drawing, there is illustrated a combined wood and coal burning stove embodying a casing 1 of cylindrical formation supported upon feet 2, the upper end of the stove casing being provided with a cover or top wall 3 having a rearwardly positioned flue opening 4, the top wall 3 being provided with a central opening 5 to be covered by a swinging plate 6 pivotally mounted as at 7 upon the top wall 3.

The interior of the stove casing 1 adjacent the bottom wall 8 is provided with a coal burning chamber, a metallic frame 9 suitably mounted within the casing 1 supporting a coal burning grate 10 positioned above the bottom wall of the stove providing an ash pit 11, access thereto being obtained through the side door 12 as clearly shown in Figs. 1 and 2. A lining of refractory material, such as fire brick 13 is supported on the frame 9 and constitutes the wall for the fire pot, access thereto being obtained through the door 14 positioned above the coal burning fire pot as shown in Fig. 2.

The wood burning chamber for the stove 90 is positioned adjacent the upper end thereof, a metallic frame 15 supporting a grate 16 with a refractory lining 17 supported on the frame 15, access being obtained to the wood burning chamber through the door 18.

A combined draft flue and ash chute is provided in the stove at the rear side thereof opposite the several doors 12, 14, and 18, and disposed beneath the flue outlet 4 carried by the top wall of the stove, and embodies sections 19 and 20 disposed rearwardly of the coal and wood burning chambers respectively, an intermediate flue section 21 being disposed between the flue sections 19 and 20 as clearly shown in Fig. 2. A horizontal partition wall 22 is disposed in the stove casing between the coal and wood burning chambers and terminates at the forward side of the adjacent flue section 21 as illustrated, the upper surface of the partition wall being 110

rearwardly inclined as at 22^a for receiving the ashes from the wood burning chamber thereabove and discharging the same into the flue section 21, the bottom wall of the 5 partition 22 having a refractory face 23 embedded therein as illustrated in Fig. 2 and overlying the coal burning chamber therebeneath.

The several dampers associated with the 10 stove include a gravity closing damper 24 swingingly mounted upon the horizontal pivots 25 adjacent the intermediate flue section 21 with the free edge of the damper 24 engaging the rear declined edge of the upper 15 wall 22^a of the partition. The lower flue section 19 is provided with a gravity closing damper 26 operated by the weight of the ashes falling thereon for discharging the 20 ashes into the pit 11. The upper damper 27 is mounted on a horizontal pivot 28 adjacent the forward edge of the upper flue section 20 and the rear edge or side of the wood 25 burning chamber as shown in Figs. 2 and 4, the damper 27 being manually operated by the rod or handle 29 extending through the side wall of the stove casing 1.

In the use of the stove, wood or coal may be burned separately or at the same time, the damper 27 being operated for regulating the use of the stove. With the damper 27 in the full line position shown in Fig. 2, both the wood and coal burning chambers of the stove may be simultaneously utilized with unrestricted communication through 35 the enclosed flue sections to the outlet flue 4. When it is desired to use the coal burning chamber alone, the damper 27 is moved to its vertical position as illustrated by dotted lines in Fig. 2, closing the wood 40 burning chamber and only establishing communication between the coal burning chamber and the outlet flue 4, and when it is desired to alone employ the wood burning portion of the stove, the damper 27 is lowered 45 to its horizontal position, thereby cutting off communication between the coal burning chamber and the outlet flue 4 as will at once be obvious from an inspection of Fig. 2. Ashes from the wood burning chamber will 50 descend through the grate 16 and be received from the inclined surface 22^a of the partition 22, falling or moving thereon into contact with the gravity closed damper 24 that may be manually operated by the externally 55 positioned handle 30 shown in Figs. 1 and 4, permitting the ashes to fall through the flue sections 21 and 19 to be received upon the gravity operating damper 26 for discharge into the ash pit 11. It is to be understood that a suitable pan or receptacle 60 may be positioned in the ash pit 11 to facilitate the removal of ashes therefrom. Attention is also called to the door 31 communicating with the chamber above the 65 partition wall 22 for purposes of cleaning

the upper surface 22^a thereof should ashes be lodged thereon. A segment device 32 positioned exteriorly of the stove casing 1 is associated with the handle 29 for operating the damper 27 to hold the same in adjusted positions as shown in Figs. 2 and 4. By providing the wood burning chamber at the upper end of the stove and above the coal burning chamber, it is possible to place wet or green wood therein for drying the 75 same by the heat rising from the coal burning chamber prior to the burning thereof.

While there is herein shown and described the preferred embodiment of the present invention, it is nevertheless to be understood 80 that minor changes may be made therein without departing from the spirit and scope of the invention as claimed.

What is claimed as new is:—

1. In a combined wood and coal burning 85 stove, a casing, a lower coal burning chamber and an upper wood burning chamber therein, a flue within the casing communicating with a flue outlet, means within the flue for controlling communication between 90 the two burning chambers and the flue outlet, said casing having an ash pit at the lower end thereof, and a gravity operating damper adjacent the lower end of the flue 95 for receiving ashes from the wood burning chamber for discharging the same into the ash pit.

2. In a combined wood and coal burning stove, a casing, a lower coal burning chamber and an upper wood burning chamber 100 therein, a flue within the casing communicating with a flue outlet, a manually operable damper within the flue for controlling communication between the two burning chambers and the flue outlet, said casing 105 having an ash pit at the lower end thereof, and a gravity operating damper adjacent the lower end of the flue for receiving ashes from the wood burning chamber for discharging the same into the ash pit. 110

3. In a combined wood and coal burning stove, a casing, a lower coal burning chamber and an upper wood burning chamber therein, a flue within the casing communicating with a flue outlet, means within the flue for controlling communication between 115 the two burning chambers and the flue outlet, said casing having an ash pit at the lower end thereof, a gravity operating damper adjacent the lower end of the flue 120 for receiving ashes from the wood burning chamber for discharging the same into the ash pit, a partition wall between the two burning chambers and having an upper surface inclined toward the flue and a gravity 125 closing damper plate positioned between the flue and partition wall.

4. In a combined wood and coal burning stove, a casing, a lower coal burning chamber and an upper wood burning chamber 130

therein, a flue within the casing communicating with a flue outlet, a manually operable damper within the flue for controlling communication between the two burning chambers and the flue outlet, said casing having an ash pit at the lower end thereof, a gravity operating damper adjacent the lower end of the flue for receiving ashes from the wood burning chamber for dis-

charging the same into the ash pit, a partition wall between the two burning chambers and having an upper surface inclined toward the flue and a gravity closing damper plate positioned between the flue and partition wall.

In testimony whereof I affix my signature.

JAMES HOWARD.
